DESIGN.

C. WEINBERG.
GIMP.

No. 19,193.

Patented July 2, 1889

UNITED STATES PATENT OFFICE.

CHARLES WEINBERG, OF NEW YORK, N. Y., ASSIGNOR TO C. WEINBERG & CO., OF SAME PLACE.

DESIGN FOR GIMP.

SPECIFICATION forming part of Design No. 19,193, dated July 2, 1889.

Application filed May 25, 1889. Serial No. 312,123. Term of patent 7 years.

To all whom it may concern:

Be it known that I, CHARLES WEINBERG, of the city, county, and State of New York, have invented and produced a new and original Design for Gimp, of which the following is a specification.

In the drawing I have represented my design for gimp by a plan view, which fully illustrates the features of the same.

10 The leading feature of my design consists in the central row of diamond-shaped figures, and the subordinate features of my design consist in the intermediate triangular-shaped figures and the raised border, which border is crossed by lines at regular intervals.

15 *a* in the design represents the diamond-shaped figures occupying the central portion of the gimp, and *b* the spaces of triangular shape between them. *c* is a raised border,

and *d* the lines, which at regular intervals cross the border *a*. These diamond-shaped figures in the design are represented as of color that contrasts with that of the spaces between them. Between the diamond-shaped figures and the triangular spaces there are 25 short transverse lines.

I claim as my invention—

A design for gimp, the same consisting of central diamond-shaped figures and triangular intermediate figures and the raised border 30 with crossing lines, substantially as shown and described.

Signed by me this 21st day of May, 1889.

CHARLES WEINBERG.
